UNITED STATES PATENT OFFICE.

WILLIAM HENCKLER, OF ST. LOUIS, MISSOURI.

VALVE-LOCK.

1,243,936.

Specification of Letters Patent. Patented Oct. 23, 1917.

Application filed February 1, 1917. Serial No. 145,961.

To all whom it may concern:

Be it known that I, WILLIAM HENCKLER, a citizen of the United States, residing at St. Louis, State of Missouri, have invented 5 certain new and useful Improvements in Valve-Locks; and I do declare the following to be a full, clear, and exact description of the invention, such as will enable others skilled in the art to which it appertains to 10 make and use the same.

This invention relates to new and useful improvements in valve locks for tanks, and more particularly to a valve lock for operating a valve in a gasolene tank of an automobile to prevent unnecessary and dangerous escape of gasolene from the tank, and also to prevent the use of the automobile when the valve is locked.

Another object of the invention is to provide a valve lock of this character which employs a type of lock which is only operable by a certain type of key, and said lock being provided with a latch to automatically hold the valve when in open position, and to 25 prevent the key from turning to close the valve until the latch is released.

Another object of this invention is to provide a device of this character which is simple and durable in construction, inexpensive to manufacture, and one which will be very efficient in operation.

With these and numerous other objects in view, my invention consists of the novel features of construction, combination and arrangement of parts which will be herein referred to and more particularly pointed out in the specification and claims.

In the accompanying drawings:

Figure 1 is a side elevation of the device applied to a tank;

Fig. 2 is a vertical section on the line 2—2 of Fig. 1;

Fig. 3 is a vertical section through the lock with the key in position so that the cylinder 45 may be turned;

Fig. 4 is a similar view showing the cylinder rotated to open position;

Fig. 5 is a front elevation of the lock;

Fig. 6 is a vertical section taken on the 50 line 6—6 of Fig. 4;

Fig. 7 is a transverse section through the lock on the line 7—7 of Fig. 3;

Figs. 8 and 9 are similar sections on the lines 8—8 and 9—9 of Fig. 3;

Fig. 10 is a transverse section taken on the 55 line 10—10 of Fig. 2;

Fig. 11 is a detail plan view of the cylinder removed from the casing; and

Fig. 12 is an end view of the cap which is secured to the top of the casing.

In describing my invention I shall refer to the drawings in which similar reference characters designate like parts throughout the several views. In the accompanying drawings, I have shown the valve lock applied to the conventional type of valve in a tank, but it will be understood that this type of valve lock is applicable to various uses and need not be limited to the use illustrated in the accompanying drawings. 60 The numeral 1 designates a valve casing having the usual type of spaced inlet and outlet openings on opposite sides of the same, and positioned in this casing is a hollow rotatable valve 2 also provided with inlet and 65 outlet ports adapted to align with the openings in the casing. Secured to the upper end of the valve casing 1 is a longitudinally extending pipe or cover 3 which protects an operating rod 4 which is connected with the 70 valve 2. The pipe covering 3 has a T joint 5 inserted intermediate its ends, and the shank portion of the same is connected with a brace 6 whereby the valve and covering 75 may be adjusted as is obvious.

Attached to the free end of the pipe covering 3 is a lock casing 7 which is mounted on a bracket 8 which is adapted to be secured to any desired type of support, on the outside of the tank. This lock casing 90 7 is open ended and is adapted to receive therein a rotatable cylinder 9 which has one end connected with the adjacent end of the operating rod 4 of the valve.

The rotatable cylinder 9 disposed within 95 the lock casing is formed with a substantially longitudinally extending slot 10 therein, and the end of the same which is connected with the rod 4 is reduced as shown at 11, and is positioned in a reduced portion 100 12 in the lock casing. The shoulders formed by these reduced portions will consequently abut when the cylinder is in position, and longitudinally positioned within the lock casing in the shoulder, is a spring pressed 105 tumbler or detent 12' which is adapted to be positioned normally in an enlarged portion 13 at the end of the slot in the cylinder. Furthermore the rotatable cylinder is held in position by means of a spring pressed 110 tumbler 14 in the lock casing which is adapted to project transversely, and co-acts with

an adjacent portion 15 positioned in an opening in the rotatable cylinder and which alines with the recess in which the tumbler 14 is positioned, when said cylinder is in 5 locked position. This cylinder is also provided with a pair of annular grooves 16, in which are positioned projecting lugs 17 from the inner wall of the lock casing adapted for engagement with the stops 17 in said 10 grooves, and are adapted to securely hold the cylinder in position and prevent movement of the same.

In the top of the lock casing 7 is a longitudinally extending slot 18 in which is 15 pivotally mounted a latch 19, said latch having one end normally positioned downwardly through the opening and against the outer surface of the cylinder, the other end of said latch being projected outwardly 20 by means of a flat spring 20 positioned beneath the same and always tending to hold it in raised position. This spring will exert a constant pressure upon the cylinder on the other end of the latch, and the cylinder 25 9 is provided with a longitudinally extending slot 21 therein, in which this end of the latch is adapted to be positioned when the cylinder is rotated a predetermined distance. This will automatically lock the 30 cylinder in position and it is necessary to release the latch by compressing the handle of the same before the cylinder may be again rotated.

The outer end of the casing 7 is screw 35 threaded and adapted to be positioned thereon is a cap 22, which is internally threaded for engagement with said end and which has its outer end formed with an opening therein with a recessed portion 23, 40 and a stop lug 24 positioned diametrically opposite said recessed portion. Through this cap and into the slot 10 in the cylinder is adapted to be positioned the actuating key 25 which forms the operating means 45 for the lock. This key is so formed that when positioned within the cylinder, the outer end of the same will strike the spring pressed tumblers and release them, so that the cylinder may be readily turned.

50 In operation when the parts of the valve lock are assembled as shown in Figs. 2 and 3 of the drawings, it will be obvious that the key 25 being positioned within the rotatable cylinder 9 will release the locking 55 tumblers and allow the cylinder to be rotated. This rotatable cylinder is so connected with the valve 2 through the operating rod 4 that when the cylinder is in locked position the valve is closed. To open the 60 valve it is only necessary to turn the key 25, whereupon the cylinder will be rotated a predetermined distance until the valve is opened. When the valve is opened the slot

21 within the cylinder will be positioned directly beneath the latch 19, whereupon 65 the end of the latch will drop into said slot, owing to the fact that the said latch is spring pressed, and any further rotation of the cylinder will be prevented. This will automatically lock the valve in open position. 70

When it is desired to release the valve it is necessary to press inwardly upon the handle portion of the latch and lift the projected end of the same from the slot 21 in the cylinder, whereupon the cylinder may 75 be once more rotated back to its first position, and upon withdrawal of the key the tumblers will automatically lock the same against additional rotation. The turning of the key is furthermore additionally 80 limited by the stop 24 in the open end of the cap 22, and the recessed portion 23 allows the key to be positioned in the cylinder when the slot therein alines with this recess. The automatic latch which locks 85 the cylinder prevents the key from turning when the valve is opened, and makes it necessary before the key can be turned or removed to release the latch.

From the foregoing description of the 90 construction and operation of my improved valve lock, the manner of applying the same to use, and the operation thereof will be readily understood, and it will be seen that I have provided a simple and efficient 95 device of this character for carrying out the objects of the invention.

I claim:

1. A device of the class described comprising a casing, a key actuated rotatable 100 cylinder in said casing, spring pressed tumblers to normally lock the cylinder against rotation and releasable upon insertion of the key, and a manually releasable latch to automatically lock the cylinder when the 105 same is rotated a predetermined distance.

2. A device of the class described comprising a casing, a key actuated rotatable cylinder in said casing, spring pressed tumblers to normally lock the cylinder against 110 rotation and releasable upon insertion of the key, said cylinder having a depression in its outer surface, a spring pressed manually releasable latch pivoted on the casing, and one end of said latch extending through 115 the casing and normally positioned against the cylinder to engage the depression therein when the cylinder is rotated a predetermined distance.

In testimony whereof I have hereunto set 120 my hand in the presence of two subscribing witnesses.

WILLIAM HENCKLER.
